UNITED STATES PATENT OFFICE.

RAFAEL, GUASTAVINO, OF BAY SHORE, NEW YORK, ASSIGNOR TO R. GUASTAVINO COMPANY, A CORPORATION OF MASSACHUSETTS.

ACOUSTICAL FACING MATERIAL FOR INTERIORS.

Application filed July 8, 1922. Serial No. 573,646.

To all whom it may concern:

Be it known that I, RAFAEL GUASTAVINO, a citizen of the United States, residing at Bay Shore, in the county of Suffolk and 5 State of New York, have invented certain new and useful Improvements in Acoustical Facing Materials for Interiors, of which the following is a specification.

This invention relates to the art of acoustics, and more particularly to the novel utilization of a natural material whereby its inherent physical characteristics may be utilized for acoustical purposes, especially for facing walls and ceilings in auditoriums 10 and the like to correct certain types of acoustical difficulties by the prevention of excessive reverberation and echo and injurious focusing of sound.

Primarily, it is the object of the invention 20 to render available for use, as an acoustical facing, structural natural stone of a porous characteristic, having intercommunicating pores or air passages throughout its body, and which, according to the present invention, 25 may be caused to extend to and open at the exposed cut surface. An example of stone of that character are certain stones of a lime formation which originally contained fossilized materials which in due process of 30 time and nature have mostly been dissolved with the result of leaving a stratified structure having air spaces and communicating channels. Heretofore, such stone has been 35 quarried and prepared in a promiscuous manner without reference to any features of the present invention which renders the same available for auditoriums and other places where it is necessary to employ a facing 40 for the walls and ceilings possessing maximum acoustical properties, and at the same time presenting pleasing decorative effects.

When stone of the character described is 45 cut or laid, according to the requirements of the present invention, it possesses the property of absorbing sound waves to such a high degree as to be exceedingly valuable as a building material for the interior of buildings, particularly for auditoriums and 50 other places where a maximum acoustical result is to be desired. In fact, according to the present invention, when stone of the particular character described is cut across the grain or strata or when selected from 55 pieces presenting such a section, and laid

either in the form of a block or slab as the facing for a wall or a ceiling, the same may be made available to absorb in excess of fifteen per centum of sounds lying in the pitch between the middle C and the third octave 60 above middle C, which are the characteristic sounds which distinguish articulate speech.

With these and other objects in view which will more readily appear as the nature of the invention is defined, the same consists 65 in the novel features and combination of features hereinafter more fully described, illustrated and claimed.

To illustrate, by way of example, the features upon which the present invention is 70 based, in the accompanying drawings,

Figure 1 is a graphic microscopic enlargement of a natural stone so cut as to provide the construction required by the present invention.

Figure 2 is a similar view showing how the patented acoustical material (referred to herein) combines with the natural stone as a facing or backing therefor.

Figures 3, 4, 5 and 6 are sectional detail 80 views, enlarged for the sake of clearness showing various ways of using the acoustical material as an interior facing.

Figure 7 is a face view of a portion of a wall constructed in accordance with the 85 present invention.

Figure 8 is a detail sectional view illustrating the feature of fastening the stone slabs or blocks to the supporting wall with 90 an anchor.

Figure 9 is a detail view illustrating the use of the invention in connection with a supporting wall surface made of wire lath and metal.

Like references designate corresponding 95 parts in the several figures of the drawings.

In carrying forward the invention there is selected a natural porous stone which, as hereinbefore stated, may be a stone of lime formation, which originally contained fossilized materials, which in due process of time and nature has mostly dissolved leaving innumerable numbers of spaces or pores in the body of the stone, which, may be made by the present invention to open 100 through the exposed face of the stone so that the latter will possess the property of absorbing sound waves to such a high degree as to be exceedingly valuable as a material for facing interiors. Also, the kind of stone 110

referred to, or its equivalent, will have sufficient hardness to stand ordinary loads, at the same time presenting a very pleasing appearance when properly tooled or processed, 5 and also susceptible of pleasing ornamentation.

In Figure 1 of the drawings, a section of the said natural stone is shown, designated by the letter A, and indicated by the number 10 1 is the general trend or line of the stratification or layers of the materials which usually make up the body of a porous stone of the kind referred to. It is preferable in preparing this stone for use to cut 15 through the same at an angle to the stratification to thereby form the outer or exposed face of the block or slab with the pores opening through such face. When the stone is so cut, it may be utilized in the manner contemplated by the present invention.

Therefore, it will be apparent that by cutting the porous stone at right angles, or at an angle generally to the line of stratification, the intercommunicating pores will open 25 through the exposed face S, which will be the face exposed to receive and absorb the sound waves generated in the auditorium or room. Hence, it is proposed to incorporate the blocks or slabs of stone, cut as described, 30 in the wall or ceiling in such a manner that the face S will be exposed to the sound waves, while the top, bottom and ends of the block or slab will be cemented or mortared as at x to the adjacent blocks or slabs as 35 shown in Figure 7.

In cases where the porosity of any particular stone is too large to absorb the audible sound waves it may be necessary to close the pores, but that can only be done by using 40 for that purpose sound absorbing material of the character described in a former patent of myself and W. C. Sabine, No. 1197956, dated September 12, 1916 (re-issued under No. 14992). When such material is used for 45 the filling of large pores in the cut stone, the effect will be to partly close up the large spaces on the face or back, or both face and back, of the stone so as to reduce the porosity to the required dimensions. The method of 50 doing this may be varied: for instance, the stone after sawing and tooling could be laid horizontally on a table and the acoustical material referred to mixed and then spread over the stone in such a manner as to fill up 55 all of the large pores, or the stone after setting may be troweled with the said acoustical material, the filling material of course to be made flush with the normal surface of the stone.

60 The combination of the natural stone with the filling of the acoustical material will give a composite material possessing a high degree of sound absorption, that is, capable of absorbing sound waves between C1 and C7, 65 and particularly between the range of C3

and the third octave above. Furthermore, the acoustical filling material may be made of the same color as the stone or of an entirely different color, thus giving a very desirable range of selection for pleasing color 70 effects.

It should be further observed that the porosity of some of the individual stones, or a large number of them, which may be selected for the purpose of the present invention, may be such that it would be advantageous not only to close part of the large pores on the surface, by the acoustical filling material above referred to, but also to back the stones or slabs with a thick layer of the 80 said patented acoustical material when the stone is set in the walls. A method of using the stone in that way would be to first cover the stone with a moderately heavy layer of the patented acoustical material on the back, 85 and allow the same to set. This material will adhere very firmly to the stone on account of its porosity or cavities and become an inseparable part thereof. The stone slabs or blocks so formed are then set on edge in 90 the wall in mortar, and fastened to the supporting wall with anchors y in the customary method of setting marble slabs, as shown in Figure 8, or it may be backed up solid with a grout of cement or mortar as shown 95 in Figure 9.

Other methods of using the stone slabs or blocks are quite numerous, but some may be briefly referred to. For instance, the stone slabs may be set vertically and spaced 100 from one-half to one inch away from the wall and the patented acoustical material above described thrown into said space and slightly rammed behind the stone, serving to bond the stone to the wall, as shown in the drawings. These methods of construction provide for materially increasing the acoustical efficiency of the stone material, because should the porosity of the stone be 110 large the sounds of high pitch will not be absorbed, but as the sound waves pass from the large pores of the stone into the small pores of the patented acoustical material, which forms the backing, they will be absorbed to a very large extent, somewhat in 115 the manner provided for by the material of graded porosity referred to in the patent aforesaid. However, in the present invention I propose to use the natural stone with the larger pores for the front facing and the 120 artificial product for the back, thus serving in a dual capacity as a backing and as a binding material between the stone and the supporting wall surface. The supporting wall surface may be of any usual masonry 125 construction of stone wall, brick wall, concrete, or wire lath and metal. This modification is shown in Figure 9 of the drawings and in that figure of the drawings it will be observed that the reference letter g design- 130

nates a metal frame to which is attached the wire lath or expanded metal *h*, and the letter *i* indicates a grout of cement or mortar applied to the wire lath or metal and upon 5 which is laid the acoustical facing consisting of the stone 1 and the sound absorbing material B previously referred to.

The several detail figures of the drawings illustrate various combinations in which the 10 natural stone material may be employed, some combinations involving air spaces and others not, but in all cases the special advantages and objects accomplished by the present invention are conserved, and it will 15 be understood that various other combinations may be employed without departing from the spirit or sacrificing any of the advantages of the invention.

In the examples shown in Figures 2 to 6 20 inclusive, A designates the natural acoustical stone, in block or slab form, B the aforesaid patented acoustical material, C mortar or cement, D air space, E any fibrous or granular material, and F the wall or base.

25 I claim:

1. An acoustical construction for auditoriums and the like consisting of a facing of porous natural stone having intercommunicating pores opening through the exposed 30 face thereof.

2. An acoustical facing for auditoriums and the like consisting of natural porous stone having its pores opening through its exposed face.

35 3. An acoustical facing for auditoriums and the like consisting of natural stone with substantially parallel stratification and having its exposed face cut at an angle to the stratification presenting open intercom- 40 municating pores for absorbing sound.

4. An acoustical material for auditoriums

and the like consisting of natural porous stone, and sound absorbing material applied to a face of said stone.

5. A composite acoustical material 45 consisting of a natural porous stone, and sound absorbing material partly filling the pores of a face thereof.

6. An acoustical facing for auditoriums and the like consisting of natural stratified 50 porous stone having an exposed acoustical face disposed at an angle to the stratification, and a sound-absorbing coating applied to a face of the stone.

7. An acoustical construction consisting 55 of a plurality of acoustical units of natural porous stone laid side by side and presenting open exposed faces, a supporting surface, and a sound absorbing filling between said supporting surface and the natural 60 stone.

8. An acoustical construction consisting of a plurality of acoustical units of natural porous stone having a face cut at an angle to stratification, a supporting wall surface, 65 and a filling of sound absorbing material disposed between said supporting wall surface and said units.

9. An acoustical construction including 70 a plurality of acoustical units of natural stone having intercommunicating pores, said units being laid in a position whereby the pores extend from front to back thereof, a supporting structure, and a body of sound absorbing material between said units and 75 the supporting structure.

In testimony whereof I hereunto affix my signature in the presence of two witnesses.

RAFAEL GUASTAVINO.
